UNITED STATES PATENT OFFICE.

CHARLES A. GUTENKUNST, OF MILWAUKEE, WISCONSIN.

STANCHION.

Application filed November 27, 1925. Serial No. 71,736.

This invention relates to improvements in stanchions.

It is one of the objects of the present invention to provide a stanchion of channel iron construction in which one of the upright members is bent at right angles at its upper end portion to form an integral arm.

A further object of the invention is to provide a stanchion having simple and effective stop means for limiting the opening movement of the stanchion.

A further object of the invention is to provide a stanchion equipped with novel, accessible and easily operated releasable latch means for retaining the stanchion in closed position.

A further object of the invention is to provide a stanchion adjustable to vary its width in closed or latched position.

A further object of the invention is to provide a stanchion which is of very simple construction, is strong and durable, is relatively inexpensive to manufacture and is well adapted for the purposes described.

With the above and other objects in view, the invention consists of the improved stanchion and its parts and combinations as set forth in the claim, and all equivalents thereof.

In the accompanying drawing in which the same reference characters indicate the same parts in all of the views:

Fig. 1 is a front view of the improved stanchion;

Fig. 2 is an enlarged sectional view taken on line 2—2 of Fig. 1;

Fig. 3 is an enlarged detail view showing the latch mechanism, part being broken away and shown in section;

Fig. 4 is an enlarged detail sectional view taken on line 4—4 of Fig. 1;

Fig. 5 is an enlarged detail sectional view taken on line 5—5 of Fig. 1;

Fig. 6 is an enlarged detail sectional view taken on line 6—6 of Fig. 1;

Fig. 7 is an enlarged detail sectional view taken on line 7—7 of Fig. 1;

Fig. 8 is an enlarged detail sectional view taken on line 8—8 of Fig. 1;

Fig. 9 is an enlarged bottom view of the stanchion taken on line 9—9 of Fig. 1;

Fig. 10 is a plan view of the stanchion

on a larger scale and reversed as to Fig. 1; Fig. 11 is a fragmentary view of a slightly modified form of the invention;

Fig. 12 is a sectional view thereof taken on line 12—12 of Fig. 11; and

Fig. 13 is an enlarged sectional view of the bottom portion of the modified form of stanchion.

Referring now more particularly to the drawings, it will appear that the numeral 15 indicates one side member or arm of the improved stanchion, and the numeral 16 indicates the other vertical arm thereof, both being formed of channel iron with the channel turned outwardly.

The arm 15 is bent at right angles medially, as at 17, to form an elongated vertical or top bar 18. A complementary vertical or top bar 19 is bolted to the upper end portion of the side arm 16, and said bar 19 is of bifurcated form and arranged for sliding engagement with the bar portion 18. The outer end portion of the bar 19 is raised, as at 20, to contact with an upstanding lug or stop 21 bolted to the outer end portion of the bar 18, to limit the outward movement of the bars 18 and 19 with respect to each other.

The lower end portions of the arms 15 and 16 are adjustably and hingedly connected together to permit opening and closing of the arms with respect to each other. To this end, shoes 22 are bolted into the channels of the lower end portions of each arm and the adjacent ends of the shoes are forked, as shown in Fig. 9, and held together by a pivot bolt 23. To adjustably secure the shoes to the arms, the lower end portion of each arm is provided with a plurality of openings 25 for registration with any of the openings 24 of each shoe, the shoe and arm being connected together by bolts 26 passed through the registering openings. By these means, therefore, the shoes and arms may be adjusted to vary the width of the stanchion when required.

A movable latch member 27 is pivotally secured to the upper end portion of the arm 16 between the bifurcated portions of the bar 19. Said latch member may be manually pressed against the tension of a coiled spring 28 and the outer engaging end of the latch is notched, as at 29.

A complementary, stationary latch member 30 depends from a bracket 31 bolted to the medial portion of the bar 18 and said member 30 is arranged for releasable engagement with the member 27 to hold the stanchion in closed position.

- The bracket member 31 is looped or oval in form, as shown in Fig. 4 to permit the bar member 19 to slide therethrough. To adjustably secure the bracket to the bar 18, said bar is formed with a plurality of openings 32 and the bracket 31 also has an opening for registration with any of the openings 32, whereby the bracket 31 may be shifted longitudinally for adjustment and retained in any adjusted position by bolt means 33. A link chain 34 is secured to the upper portion of the bracket 31 for suspending the stanchion.
- It will thus be seen that the arms of the stanchion hingedly move on the pivot bolt 23, and that the top bars 18 and 19 are slidably associated. The manually operated latch 27 holds the stanchion in closed position. The width of the stanchion may be varied by adjusting the shoes 22 and corresponding adjustments of the upper portion of the stanchion are effected by means of the shiftable bracket 31 which carries the stationary latch member 30.

In Figs. 11, 12 and 13 a slightly modified form of the invention is illustrated. As shown in Figs. 11 and 12, the channel

of the arms 15' and 16' is turned inwardly to receive wooden strips 35 held in place by wood screws 36. The lower end portions of the arms are also somewhat modified (see Fig. 13) and the shoes 22' are secured to the outer portions of the arms.

From the foregoing description it will be seen that the improved stanchion is of very simple and novel construction, and is well adapted for the purposes set forth.

What I claim as my invention is:

A stanchion, comprising a pair of vertical channeled arms, one of said arms being bent to form a top extension and the other of said arms having a bifurcated top bar secured thereto slidably engaging said bent extension between said bifurcated portions, both of said top members being formed with stops at their outer ends for engagement with each other, shoe members pivotally secured together and adjustably secured to the lower end portions of the arms, an upstanding looped bracket adjustably secured to said bent extension and enclosing said bifurcated top bar, a latch member carried by said bracket, and a pivotal latch carried by the upper portion of an arm for releasable engagement with said first mentioned latch member to hold the stanchion in closed position.

In testimony whereof, I affix my signature.

CHARLES A. GUTENKUNST.
